(57) **CLAIM**

The ornamental design for rack for refrigerating machine, as shown and described.

DESCRIPTION

FIG. 1 is a perspective view of the front, right, and top sides a rack for refrigerating machine, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown in a condition of use;

FIG. 9 is another perspective view thereof, shown in another condition of use;

FIG. 10 is another perspective view thereof, shown in another condition of use;

FIG. 11 is another perspective view thereof, showing two racks in another condition of use; and,

FIG. 12 is another perspective view thereof, showing two racks in another condition of use.

The broken lines shown in the drawings represent unclaimed environment and form no part of the claimed design.

1 Claim, 12 Drawing Sheets
